DEVICE FOR OPENING SEALED CONTAINERS

Ozro N. Wiswell, Los Angeles, Calif., assignor to
Swingspout Measure Company, Los Angeles,
Calif., a corporation of California

Application April 22, 1933, Serial No. 667,405

25 Claims. (Cl. 221—23)

This invention relates to a device for opening sealed containers and it is a general object of the invention to provide a practical, convenient and effective device for opening cans or sealed containers.

Liquids, such as lubricating oils and the like, are being marketed in sealed containers bearing labels indicating their contents, so that there can be no substitution or adulteration of the products.

In the marketing or selling of lubricating oil in such containers, it is desirable to empty the entire contents of the container directly into the dispensing receptacle or measure. The devices that have been introduced to facilitate the opening of sealed containers and for draining their contents into dispensing receptacles are not entirely satisfactory, as they usually form inwardly projecting ridges or beads around the openings they form in the container that trap or retain some of the contents in the container, and in certain types of devices, the container is pushed on to cutters mounted in the dispensing receptacle and the discharging contents cover the exterior of the container so that a considerable amount of oil is lost and the container and receptacle are soiled by the clinging oil and are inconvenient to handle.

An object of the present invention is to provide a device for opening sealed containers that is easy and convenient to use and that does not allow the contents of the container to spill or soil the exterior of the container, or the dispensing receptacle or measure.

Another object of the invention is to provide a device for opening cans or sealed containers that guides and holds the container in a tipped position and makes a clean opening in an end of the container that extends inwardly from the lowermost edge of the container so that its entire contents are quickly discharged and are entirely drained from the container.

It is another object of the invention to provide a device for opening cans or sealed containers that may be attached to or applied to a dispensing receptacle or measure, and that is such that the contents of the opened container are drained directly into the receptacle.

It is another object of the invention to provide a device of the character mentioned that is small and compact and that does not extend into the interior of the dispensing receptacle, or interfere with the pouring of liquids into the receptacle.

It is another object of the invention to provide a device of the character mentioned that may be mounted on the upper end of a receptacle and

that cuts an opening in a container upon the container being pushed downwardly onto it, the device guiding and supporting the container so that the downward force exerted on it acts downwardly and inwardly toward the center of the receptacle so that the receptacle has no tendency to upset or tip.

It is another object of the invention to provide a device of the character mentioned including a novel and improved form of cutter that operates to make a clean opening in an end of the container that extends inwardly from the lowermost edge of the tipped container so that all of its contents may freely drain through the opening.

It is another object of the invention to provide a device of the character mentioned that includes a guide for guiding the can or container on to the cutter that also operates as a safety shield to prevent any one from being injured by the cutter.

It is another object of the invention to provide a device of the character mentioned that is adapted to open containers varying considerably in shape and size.

It is another object of the invention to provide a device for opening sealed containers that may be easily and quickly attached to and removed from a dispensing receptacle or measure.

Other objects and features of the invention will be best and fully understood from the following detailed description of typical forms and applications of the invention, throughout which description reference is had to the accompanying drawings, in which:

Fig. 1 is a side elevation of one embodiment of the invention illustrating it arranged on a typical dispensing measure. Fig. 2 is an enlarged fragmentary vertical sectional view of the upper portion of the receptacle showing the opened container in position on the device. Fig. 3 is a plan view of the cutter before being shaped or formed.

Fig. 4 is a fragmentary horizontal detailed sectional view taken substantially as indicated by line 4—4 on Fig. 2. Fig. 5 is a fragmentary vertical detailed sectional view illustrating a form of fastener for detachably connecting the device with the handle of a receptacle. Fig. 6 is an enlarged vertical detailed sectional view taken substantially as indicated by line 6—6 on Fig. 5.

Fig. 7 is a view similar to Fig. 4 illustrating a container of rectangular cross section being opened by the device. Fig. 8 is a side elevation of another embodiment of the invention illustrating the body and cutter in vertical cross sec-

tion, and Fig. 9 is a side elevation of still another form of the invention.

The device provided by this invention is adapted to be embodied in forms for use in various situations and for opening containers of various characters. Throughout the following detailed disclosure, I will describe several typical forms and applications of the invention, it being understood that the invention is not to be considered as restricted to the specific embodiments or applications about to be set forth, but is to be taken as including any features or modifications that may fall within the scope of the claims.

In Figs. 1 to 7 inclusive, of the drawings, I have illustrated the invention in connection with a popular type of dispensing receptacle or measure R used for handling lubricating oil, and the like. The receptacle R is an open topped vessel formed of sheet metal, or the like, and having a swingable discharge spout 10 for facilitating the dispensing of the oil. An inwardly projecting lip 11 is provided along the upper edge of the receptacle R. The lip 11 is transversely curved, being upwardly convexed, and is provided at its inner edge with an inwardly projecting horizontal flange 12 for indicating the level to which the receptacle may be filled when measuring a definite quantity of liquid. In the particular receptacle illustrated, radial reinforcing ridges 13 are provided on the lip 11. A suitable handle 14 is provided on the receptacle R and its upper end portion 15 is attached to the side or wall of the receptacle adjacent the lower edge of the lip 11.

The embodiment of the invention illustrated in Figs. 1 to 4 inclusive of the drawings includes, generally, a body 16, a cutter 17, and a guide 18 for guiding a can or sealed container into proper engagement with the cutter 17.

The body 16 is adapted to be attached to the receptacle R and is shaped and proportioned to effectively seat on its lip 11. It is to be understood that the body 16 may be shaped and constructed for application to measures or receptacles of various shapes and sizes. In the particular form of the invention illustrated in the drawings, the body 16 is of curved vertical cross section having a rounded or convexed upper surface and a recess 20 in its lower side for receiving the lip 11. The inner edge 21 of the body seats on the horizontal flange 12 and spaced horizontal flanges 22 project inwardly from the inner end of the body. The spaced flanges 22 have flat horizontal upper sides for carrying the cutter 17 as will be subsequently described. Spaced lugs 23 project from the under sides of the flanges 22 and engage under the horizontal flange 12 of the receptacle. The ears or lugs 23 engage under the flange 12 at circumferentially spaced points and effectively connect the body 16 with the lip 11. A projection 24 is provided on the outer side of the body 16 to seat on the upper face of the part 15 of the handle 14. The projection 24 is adapted to be attached to the handle part 15 in any suitable manner. In the form of the invention illustrated in Figs. 1 to 4 of the drawings, a bolt or screw 25 extends through openings in the projection 24 and handle part 15 to connect the projection with the handle. It will be apparent how the lugs 23 engaging under the flange 12 and the projections 24 attached to the handle part 15 by the screw 25 securely connect or attach the body 16 to the receptacle. It is to be noted that the body 16 does not extend or project into the interior of the receptacle R and that its flanges

22 extend only short distances across the open top of the receptacle.

The cutter 17 is operable to penetrate or cut an opening in an end of a container C pushed or forced downwardly on to it so that the contents of the container may discharge directly into the receptacle R. The cutter 17 is mounted or supported on the flanges 22 and projects upwardly a considerable distance above the top of the receptacle R. The cutter 17 is substantially U-shaped in horizontal cross section having spaced vertically disposed side parts 27 and a curved outer part 28 connecting the spaced parts 27. It is an important feature of the invention that the cutter 17 is inclined downwardly and inwardly toward a point in the central vertical axis of the receptacle R so that the force exerted on the cutter in opening the container C is directed inwardly and diagonally relative to the receptacle R, and has no tendency to tip or upset the receptacle R. In accordance with the invention, the cutter 17 is detachable from the body 16 so that it may be removed for sharpening or may be replaced if desired or found necessary. Outwardly projecting horizontal ears 29 are provided on the lower ends of the side parts 28 and seat on the flanges 22. Screws 30 detachably connect the ears 29 to the flanges 22.

The upper ends of the side parts 27 of the cutter are inclined upwardly and outwardly to the upper end of the connecting part 28. A continuous sharpened cutting edge 31 extends along the upper edge of the cutter 17, that is, it extends along the upper inclined ends of the side parts 27 and forms a point 32 at the upper end of the connecting part 28. The cutting edges 31 in extending along the upwardly and outwardly converged upper ends of the side parts 27 and in joining at the extreme upper end of the cutter, provide a comparatively sharp cutting point 32. The inner side of the cutter 17 is bevelled to provide the cutting edges 31, and the outer side of the cutter is preferably smooth to join the bevelled surfaces at the edges 31. The cutter 17 may be constructed from a flat blank of the character illustrated in Fig. 3 of the drawings. In accordance with the invention, the opening or space between the lower ends of the side parts 27 continues or extends upwardly into the body of the cutter to provide a drain opening 33. A comparatively narrow tongue 34 extends downwardly from the upper end of the drainage opening 33 to guide the lower bead 35 of the container C. In practice, the extreme lower end of the tongue 34 may be bent inwardly to prevent the bead 35 from binding or becoming caught under the end of the tongue. The cutter 17 may be proportioned so as to form a comparatively large opening in the end of a container. The curvature of the connecting part 28 of the cutter is such that the cutter is adapted to be employed to open containers of rectangular cross section in the manner illustrated in Fig. 7. When the container C is pushed or forced downwardly on to the cutter 17, the point 32 pierces the end 36 of the container at a point immediately adjacent the bead 35 and continued downward pressure on the container causes the cutting edges 31 to make a substantially U-shaped cut in the end 36. The cutter 17 in being bevelled at its inner side to provide the cutting edges 31, causes the material between the sides of the cut to be rolled inwardly as illustrated at X in Fig. 2 of the drawings. The straight or even outer side of the cutter 17 terminating at the cutting edges 31

31, permits the cutting edges to make a clean cut in the end of the container without producing an inwardly projecting bead or ridge along longitudinal edges of the cut and without distorting the container.

The guide 18 is provided to guide and maintain the container C in proper cooperation with the cutter 17 and to prevent the user from being injured by the cutter. The guide 18 projects upwardly from the body 16 and is spaced a short distance outwardly from the cutter 17. In the embodiment of the invention being described, the guide 18 is integral with the body 16. The guide 18 is inclined upwardly and outwardly at the same angle as the cutter 17 and is spaced outwardly from the cutter a sufficient distance to pass the bead 35 of the container C with suitable sliding clearance. The inner surface or side 40 of the guide 18 is adapted to be engaged by the container C and is shaped so as to effectively guide the container on to the cutter 17 and to steady or stabilize the container during its downward movement.

The guide 18 may be shaped and proportioned so as to guide containers of any particular or specific shape on to the cutter 17. In the particular case illustrated in the drawings, the guide 18 is of curved horizontal cross section so as to handle or guide cylindrical containers. The diameter of curvature of the guide 18 is preferably sufficiently large to allow the guide 18 to accommodate cylindrical containers varying considerably in size and to permit the device to be used in opening containers of rectangular or polygonal cross section in the manner illustrated in Fig. 7. In the form of the invention illustrated in the drawings, the guide 18 extends from one end of the body 16 to the other and projects a substantial distance above the upper end of the cutter 17. The upper end of the guide 18 may be suitably curved as illustrated in the drawings. It will be apparent that the guide 18 operates to shield the cutter 17 and to prevent accidental contact with the cutter.

It is believed that the operation of the form of the invention illustrated in Figs. 1 to 4 inclusive of the drawings will be readily understood from the foregoing detailed description. To open the container C, it is slid downwardly on the inner surface 40 of the guide 18 so that the point 32 of the cutter penetrates the end 36 of the container at a point immediately adjacent the bead 35. A downward and inward pressure or push on the upper end of the container C forces it downwardly on the cutter 17 so that the cutting edges 31 of the cutter operate to make a U-shaped cut. As described above, the cutter in being sharpened at its inner side to provide the edges 31, operates to roll the material between the sides of the cut inwardly in the manner illustrated in Fig. 2 of the drawings. The guide 18 operates to hold the container C in proper cooperation with the cutter 17 as it is forced downwardly on the cutter. The force or pressure exerted on the container C when it is pushed on to the cutter 17 acts downwardly and inwardly toward the centre of the receptacle R and does not cause the receptacle to be tipped or overturned. It is preferred to push the container C downwardly and inwardly on the cutter 17 at approximately the same angle as the guide 18, and the cutter; however, a straight downward force exerted on the container C during opening of the container will not overturn the receptacle R or prevent the proper operation of the cutter 17, as the guide 18 operates to guide the cutter

downwardly in an inclined or tipped position and maintain it in proper cooperation with the cutter. As the opening is formed in the bottom or end 36 of the container C, the contents of the container discharge or drain downwardly through the lower end of the cutter and between the flanges 22 directly into the receptacle R. The material between the spaced parts of the guide, in being rolled back as indicated at X in Fig. 2 of the drawings, provides a large unobstructed opening in the end of the container in direct vertical alignment with the space between the side parts 27 of the cutter and the body flanges 22. The drainage opening 33 in the cutter 17 permits the free discharge and draining of the contents of the container from the outer side of the cutter. As the container C is tipped or inclined, its contents may freely drain through the opening formed by the cutter 17. There is no upstanding ridge or bead formed along the longitudinal and lower edges of the opening made by the cutter 17, and fluid cannot be trapped in the lower end of the inclined container. Very little force or pressure is required to push the container on to the cutter and the container is easily removed from the cutter after being opened and drained. In practice, the cutter 17 makes an opening in the end of the container that extends inwardly from the bead 35 and thus allows for the drainage of all the liquid from the container. The device may be easily and quickly applied to dispensing receptacles or measures now in use or may be embodied in the receptacles when manufactured. The cutter 17 is attached to the body 16 so that it may be readily removed for replacement or sharpening. The device does not project into the interior of the receptacle R and does not extend a substantial distance across the open end of the receptacle and therefore does not interfere with the use of the receptacle as a measure for liquids poured into its upper end.

Figs. 5 and 6 of the drawings illustrate a spring or clip fastening means for detachably connecting the body 16^a of the device with the handle 14 of the receptacle. A clip 50 is attached to the under side of the body projection 24^a and is substantially U-shaped, having a lower part 51 adapted to engage under the upper portion 15 of the handle. The lower portion 51 of the clip may be passed under the handle part 15 by turning the device horizontally toward the handle part to the position illustrated in Figs. 5 and 6. The body 16^a of the device may be provided with lugs 23 of the character described above for engaging under the flange 12 of the receptacle and the device may be attached to the receptacle by hooking the lugs 23 under the flange 12 and then turning the body of the device along the lip 11 to bring the clip part 51 into holding engagement with the under side of the handle part 15. It will be apparent how the lugs 23 and clip 50 operate to effectively attach or connect the device with the receptacle. The device may be easily detached from the receptacle by turning it in a direction to disengage the clip part from the handle part 15 to allow the lugs 23 to be released from the flange 12.

Fig. 7 of the drawings illustrates a container 60 of square or polygonal cross section arranged in operative position on the cutter 17. Square or polygonal containers usually have rounded corner portions 61 as illustrated, and the rounded connecting portion 28 of the cutter 17 is adapted to pass through the end of the container and slidably engage the inner side of one of the rounded corner parts 61 of the container walls. Where the device is to be exclusively employed for opening

square containers, the guide 18 may be shaped to accommodate them; however, the guide 18 curved as illustrated is effective in guiding polygonal containers on to the cutters 17.

5. The form of the invention illustrated in Fig. 8 of the drawings includes a body 70 detachably mounted on a standard or post 71. The post 71 projects upwardly from a horizontal base 72 which may be shaped and constructed to support a receptacle 73. The body 70 of the device is provided in its lower end with a vertical opening 74 for receiving the upper end portion of the post 71. A pin or key 75 may be provided to prevent turning or rotation of the body 70 on the post 71. The cutter 76 may be identical with the cutter 17 described above with the exception that it is provided with laterally projecting ears 77 detachably connected with the inner sides of the body 70. The guide 78 for slidably guiding the container on to the cutter 76 may be an integral part of the body 70 and may project downwardly below the active parts of the cutter 76 to prevent splashing or spilling of the contents of the container. The form of the invention illustrated in Fig. 8 of the drawings may be used in various situations and may be constructed to open containers of various characters.

Fig. 9 of the drawings illustrates another manner of mounting the form of the device illustrated in Fig. 8. A bracket 80 is attached to a shelf or suitable horizontal support 81. An upwardly projecting member 82 is provided on the outer end of the bracket 80 and extends into the opening 74 in the lower side of the body 70. The body 70 is detachable or removable from the member 82. A key or pin 83 may be provided to hold the body 70 against turning or rotation on the member 82. The forms of the invention illustrated in Figs. 8 and 9 of the drawings may be used in restaurants, or the like, for opening sealed containers of food and may be easily and quickly detached from their mountings or supports so that they may be washed or cleaned.

In my copending application Serial Number 45 678,062, I have illustrated and described a device for opening sealed containers similar generally to the device described herein but differing therefrom in having a cutter carrying base having bearing cooperation with the receptacle along the 50 major portion of its upper end. In my copending application Serial Number 705,890 I have illustrated and described a device comprising a cutter within a receptacle and means for guiding a container to the cutter. No claim is made 55 herein to a base having bearing cooperation with the major portion of the upper end of a receptacle or to a cutter and guide means in a receptacle as these features are broadly claimed in my copending applications.

60 Having described only typical forms and applications of my invention, I do not wish to limit or restrict myself to the typical forms or applications herein set forth, but wish to reserve to myself any variations or modifications that may appear to those skilled in the art or fall within the scope of the following claims:

Having described my invention, I claim:

1. In combination, a receptacle for holding fluid, a body attached to the receptacle at a point above the fluid containing limits of the receptacle, and a cutter on the body projecting from the upper end of the receptacle adapted to penetrate a container forced downwardly on it.
2. In combination, a receptacle for holding fluid, and a device for opening containers includ-

ing, a body adapted to be attached to the receptacle, and a cutter on the body projecting from the upper end of the receptacle adapted to penetrate a container forced downwardly on it, the cutter being inclined downwardly and inwardly toward the center of the receptacle.

3. A device for opening containers including, a body adapted to be arranged on the upper end of an open-topped receptacle normally having a vertical longitudinal axis, a cutter on the body projecting upwardly beyond the upper end of the receptacle, and means for guiding a container downwardly and inwardly onto the cutter to be penetrated thereby.

4. A device for opening containers including, an open-topped receptacle for holding fluid, a body arranged on the upper end of the receptacle, an upwardly projecting cutter on the body, and an upwardly projecting guide on the body for guiding a container downwardly and inwardly on the cutter.

5. In combination, a receptacle for holding fluids, and a device for opening containers including, a body on the upper end of the receptacle, a cutter on the body projecting upwardly from the upper end of the receptacle, the cutter being substantially U-shaped in horizontal cross section and having an inclined cutting edge on its upper end terminating in a point, and means on the body for guiding a container downwardly onto the cutter to be opened thereby and have its contents drain into the receptacle.

6. A device for opening containers including, a body, means for attaching the body to the upper end of an open topped receptacle, an upwardly projecting cutter on the body, the cutter being inclined downwardly and inwardly relative to the vertical axis of the receptacle, and a part on the body projecting upwardly from the body and having a surface spaced from and of the same 40 inclination as the cutter and being operable to guide a container onto the cutter.

7. In combination, an open topped receptacle having a clear accessible upper end, and a device for opening containers, including a cutter, means mounting the cutter on the upper end of the receptacle to project therefrom in a position where it is inclined downwardly and inwardly toward the center of the receptacle, and means for guiding a container downwardly and inwardly onto 50 the cutter.

8. In combination, an open topped receptacle, and a device for opening containers, including a cutter, means mounting the cutter on the upper end of the receptacle in a position where it is 55 entirely above the liquid containing limits of the receptacle, and means for guiding a container onto the cutter to be opened thereby to discharge its contents into the receptacle.

9. In combination, an open topped receptacle 60 for holding fluid, and a device for opening containers, including a cutter having spaced side parts and a portion connecting said parts, the cutter having cutting edges extending along the upper edges of the said parts converging to a 65 point on the upper end of said portion, means mounting the cutter on the upper end of the receptacle so that the said portion is inclined downwardly and inwardly relative to the center of the receptacle, and means for guiding a container 70 onto the cutter to be opened thereby.

10. In combination, an open topped receptacle, and a device for opening containers, including a cutter having spaced side parts and a portion connecting said parts, the cutter having cutting 75

edges extending along the upper edges of the said parts converging to a point on the upper end of the said portion, means mounting the cutter on the upper end of the receptacle so that the 5 said portion is inclined downwardly and inwardly relative to the center of the receptacle and so the said portion forms its outer side, and a guide on the said means having a container guiding face extending parallel to and spaced from said portion of the cutter.

10 11. A device for opening containers including, a cutter comprising a body having spaced substantially vertical side parts and an inclined portion connecting the said parts, there being cutting 10 edges on the upper ends of the side parts inclined in the same direction as the said portion and converging to a point on the upper end of said portion, and a guide having a surface parallel to and spaced from said portion of the cutter engageable by the outer side of a container and operable to guide a container so that said point pierces a wall of the container immediately adjacent the point where it joins said side, there being a drain opening in the lower end part of 20 said portion of the cutter.

12. A device for opening containers including, a cutter comprising a body having spaced substantially vertical side parts and an inclined portion connecting the said parts, there being cutting 25 edges on the upper ends of the side parts inclined in the same direction as the said portion and converging to a point on the upper end of said portion, means for mounting the cutter on the upper end of a receptacle so that said portion of the cutter is inclined downwardly and inwardly relative to the center of the receptacle, and a guide on the said means having a surface parallel to and spaced from said portion of the cutter operable to slidably guide a side wall of 30 a container so that an end of the container is pierced by the said point immediately adjacent the line where it joins said side wall.

13. A device for opening containers and adapted for use on a receptacle, said device including, 45 a body, means for detachably mounting the body on the upper end of the receptacle, an upwardly projecting cutter on the body, and a guide of less than 180° extent on the body for guiding a container downwardly onto the cutter to be opened thereby.

14. A device for opening containers and adapted for use on a receptacle having a handle and an inwardly projecting flange on its upper end, said device including, a body, an upwardly projecting cutter on the body and means for detachably connecting the body to the upper end of the receptacle including a lug on the body adapted to engage under the said flange, and a part on the body adapted to releasably connect 50 with the handle.

15. A device for opening containers including, a body, means for attaching the body to the upper end of an open topped receptacle, an upwardly projecting cutter on the body, the cutter being inclined downwardly and inwardly relative to the vertical axis of the receptacle, the cutter being operable to make an opening in an end of a container adjacent its outer edge, and a guide on the body operable to guide the container downwardly onto the cutter and to hold the container inclined so that the opening formed therein is at its lowermost edge.

16. A device for opening containers including, 75 a body, means for attaching the body to the upper end of an open topped receptacle, an up-

wardly projecting cutter on the body, the cutter being inclined downwardly and inwardly relative to the vertical axis of the receptacle, and a part on the body projecting upwardly from the body and having a surface spaced from and of the same inclination as the cutter and being operable to guide a container onto the cutter, the said part projecting upwardly beyond the cutter to shield the cutter.

17. A device for opening containers including, 10 a body, a cutter projecting upwardly from the body, the cutter having spaced substantially vertical side parts and an inclined portion connecting the side parts, there being a cutting edge on the upper end of the cutter adapted to pierce 15 a container forced downwardly on the cutter, and means for guiding the container onto the cutter at the same inclination as the said portion, there being an opening in the lower end of the cutter where the said parts join said 20 portion to allow the contents to drain from the container.

18. In combination, an open-topped receptacle having an inwardly projecting rim on its upper end, and a device for opening containers 25 including a body on said rim, and a cutter projecting upwardly from the body to open a container forced onto it.

19. In combination, an open-topped receptacle having an inwardly projecting rim on its 30 upper end, and a device for opening containers including a body seated on and shaped to conform to said rim, and a cutter on the body inclined toward the center of the receptacle and adapted to open a container forced onto it. 35

20. In combination, an open-topped receptacle having a rim on its upper end defining its liquid measuring limits, and a device for opening containers including a body on said rim, 40 a cutter projecting upwardly from the body, and a guide on the body for guiding a container onto the cutter to be opened thereby.

21. In combination, a portable liquid receptacle having a clear accessible open upper end and a shiftable discharge spout, and a device for 45 opening containers including a base seated on the upper end of the receptacle, a cutter projecting upwardly from the base and adapted to cut an opening in a container pushed downwardly onto it, and a part on the base for guiding the container on the cutter. 50

22. In combination, a portable liquid receptacle having a free accessible open upper end, and a container opening device including a base to be removably seated on the upper end of the 55 receptacle, and a projecting cutter on the base to open a container forced onto it to drain into the receptacle.

23. A can opening device for use on an open topped liquid receptacle including a body to be 60 arranged on the upper end of the receptacle, a cutter on the body projecting upwardly from the receptacle, and adapted to cut an opening in a can forced downwardly on it, and an upwardly projecting guide on the body for guiding the 65 can on the cutter, the cutter having an opening in its wall to allow fluid to drain out of the can from around the cutter.

24. A container opening device for use on an open topped receptacle including, a base adapted to be removably seated on the upper end of the receptacle, a lip on the base depending over the edge portion of the receptacle and extending along a substantial part of the upper end of the receptacle to prevent lateral displacement of 75

the base from the receptacle, and an upwardly projecting cutter on the base for cutting an opening in a container forced upon it.

25. A container opening device for use on an open topped receptacle having an inwardly projecting rim on its upper end, said device including, a body arranged on said rim of the con-

tainer, a cutter projecting upwardly from the body to open a container forced on it, and means for detachably connecting the body to the receptacle, said means including a part on the body for engaging under the rim.

OZRO N. WISWELL.
